CLAIM

The ornamental design for an apparatus for gas distribution as shown and described.

DESCRIPTION

FIG. 1 is a front elevation view of an apparatus for gas distribution view showing our new design;

FIG. 2 is a left elevation view thereof;

FIG. 3 is a right elevation view thereof;

FIG. 4 is a rear elevation view thereof;

FIG. 5 is a top plan view thereof;

FIG. 6 is a bottom plan view thereof;

FIG. 7 is a first isometric view thereof;

FIG. 8 is a second isometric view thereof; and,

FIG. 9 is a third isometric view thereof.

The broken lines shown in the figures are for the purpose of illustrating portions of the apparatus for gas distribution and form no part of the claimed design.
